UNITED STATES PATENT OFFICE.

SAMUEL OLSON, OF CHICAGO, ILLINOIS, ASSIGNOR TO SAMUEL OLSON & COMPANY, OF CHICAGO, ILLINOIS, A CORPORATION OF ILLINOIS.

TRAY-ELEVATOR GUIDE.

Original application filed November 27, 1920, Serial No. 426,775. Divided and this application filed November 10, 1925. Serial No. 68,129.

This application is a division of my application Serial No. 426,775 filed November 27, 1920 upon which Letters Patent No. 1,560,720 were issued November 10, 1925.

5 This invention relates to an elevator of the type shown and described in my Patent No. 1,825,857, issued December 23, 1919, and its purpose is to provide certain features of construction for an elevator of that type 10 with a view to reducing the cost of manufacture without impairing the efficiency of operation. The novel features are herein-after described and shown in the drawings and are particularly indicated by the claims.

15 In the drawings:—

Figure 1 is a sectional plan view of an elevator of the type to which this invention relates.

Figure 2 is an elevation of the same, being 20 taken partly in section.

Figure 3 is a fragmental plan view showing one of the flights provided with the form of guide follower indicated in Figures 1 and 2.

25 Figure 4 is a fragmental plan section showing a modified form of guide and follower.

Figure 5 is also a fragmental plan section showing another modification.

30 Figure 6 is a fragmental plan section of a further modification of the guide and follower.

Referring first to Figures 1 and 2, it will be noted that this type of elevator consists 35 of two pairs of chains, 1, mounted for vertical travel about suitable head wheels, 2, and foot wheels, 3, which are preferably toothed wheels for positive engagement with the chain links; and that said chains are 40 arranged in pairs, the two chains of each pair being connected by flights in the form of angled shaped members whose vertical arms, 4, are attached to the links of the two chains while their horizontal arms extend 45 toward the opposite pair of chains and in horizontal registration with similar flights for supporting loads such as trays of the type commonly used in restaurants or cafeterias for carrying dishes. Thus each pair 50 of chains, 1, with its attached flights, constitutes a belt mounted for vertical travel, and for steadyng these belts particularly

at their load-supporting plies, Figure 1 shows guide lugs, 13, extending beyond the angled shaped members to serve as guide followers engaging between vertically extending guide rails, 9 and 10, laterally adjacent the belts.

As indicated in Figure 3, the lugs, 13, are 55 formed as extensions of lugs, 12, which are integral with certain links of the chains, 1, and by which the vertical arms, 4, of the flights are attached to the chains. The guideways for the lugs, 13, are in the form of grooves produced by nesting the angle 60 rails, 10, with the angles, 9, as clearly shown in Figure 1, and the extensions of the lugs, 12, which carry the parts, 13, are offset back from the plane of the flight arms, 4, so that both of the angle rails, 9 and 10, may also 65 be disposed back of this plane to leave ample clearance for trays entering upon or leaving the load-supporting arms, 5, of the flights. In the particular arrangement shown in Figure 1, a horizontally traveling 70 belt, 7, passes between the vertically moving flights of the elevator for receiving trays therefrom as the flights descend past the plane of the belt, 7. When the trays are thus handled entirely by mechanical means, 75 it is particularly important to avoid any obstruction in the path of movement, and this is the purpose of placing the guideways 80 back of the planes of the flight arms, 4. The belt, 7, and the elevator may be geared 85 in timed relation as by means of bevel gears shown at 8. In addition to the vertical arms, 4, of the flights, the load-carrying spaces between the chains, 1, may present a practically continuous wall by providing 90 plates, 6, secured to the chains between successive flights. As indicated in Figure 3, the guide lug, 13, may be vertically extended for a considerable distance so as to give 95 stability to the flight and prevent its horizontal arm, 5, from twisting away from the horizontal plane under the load.

Figure 4 suggests a modified use of the lug, 13, by positioning the chain link so that the lug extends just flush with the extreme 100 lateral edge of the belt formed by the end of the flight. The lug, 13, being offset from the plane of the flight arm, 4, provides a space into which the single guide rail, 14,

may extend for engagement on one side by the lug, 13, and on the other side by the rear face of the flight arm, 4.

In Figure 5 I have shown another way of securing proper guidance for the vertically traveling belts. In this arrangement the chains, 1^b, are of the pintle type, and the pivots or pintles thereof are formed with extensions, 16, which may carry antifriction rollers, 15, if desired, to reach into the grooves formed by the nested guide rails, 9^a and 10^a. If preferred, the extensions, 16, may be kept within the dimensions of the flights themselves, producing a slightly more compact structure than that shown in Figure 1.

Figure 6 shows the chain, 1^c, constructed of ordinary links as in Figure 3. Separate guide followers in the form of short Z-bars, 17, are attached to the vertical arms, 4, of the flights, independently of the chains and with their flanges, 18, extending into the guideway formed by the nested angle rails, 19 and 20. This has the advantage of using standard parts for the chains and other elements, the Z-bars being the only special fittings required.

It will be evident that in all the foregoing structures the necessary guidance is secured in a more economical way than that suggested by my former Patent No. 1,325,857 in which one arm of each of the flights is made longer than the other arm to provide guide lugs, and these lugs are offset at one side of the belt to carry them back of the plane of the vertical flight arms so as to avoid obstructing the trays. By making the guide lugs as separate members, it becomes possible to cut off the flights squarely at each

end, thus saving considerable time in making these parts, and particularly if the guide lugs are provided as integral parts of the chain, no extra time is required for applying them to the flights.

I claim:—

1. In combination with the two vertically traveling belts, each composed of a pair of chains mounted for vertical travel with angle rails horizontally connecting the chains of each pair, and each disposed with one arm extending vertically and secured to the chains, and with the other arm projecting horizontally therefrom, guides extending laterally adjacent one chain of each pair, and means on the chains positioned back of the vertical arms of said angle rails and extending laterally to engage said guides.

2. An elevator in combination with a pair of vertically traveling chains with transverse load supporting means connecting them, a vertically extending guide laterally adjacent one of said chains and followers at intervals on said chain extending laterally therefrom to engage said guide.

3. An elevator comprising four chains mounted for parallel vertical travel with angle rails connecting them in pairs and horizontally registered with each other for supporting loads between the two pairs of chains, together with guide lugs on the links of said chains and spaced apart more widely than the angle rails of opposing pairs for engaging vertical guide rails extending laterally adjacent said chains.

In testimony whereof I have hereunto set my hand at New York, this 9th day of November, 1925.

SAMUEL OLSON.
